WIRE LINE JAR TOOL

William E. Barnes, Beaumont, Tex., assignor to Sun Oil Company, Philadelphia, Pa., a corporation of New Jersey

Application May 18, 1955, Serial No. 509,281

3 Claims. (Cl. 255—27)

This invention relates to a well tool and particularly to that class of well tools run on a cable in conjunction with other well tools and appliances, and specifically used to loosen these other tools from binding in the tubing by a jarring action.

An object of this invention is to provide a jarring tool that is operable to effect a controlled jarring action.

Another object is to provide a novel cable tool in which a predetermined jarring force may be established and is unfailingly operative.

Still another object is to provide a tool of the character stated capable of repeated action, in which the force effected on returning it to the operating position for repeated jarring blows is minimized.

These and other objects are attained by a jarring tool of the usual hammer and anvil type incorporating a magnetic means as the restraining element. Magnetic means of selected field force forms the opposed fixed and movable sections of the jar tool. Upon application of an upward lifting force on the suspending cable, sufficient to overcome the magnetic attraction holding the magnetic means together, the restraining force is overcome, and the hammer portion sharply released to strike on the anvil. Controlled lowering of the cable suspended hammer allows the magnetic means to reengage without striking a downward drive to repeat the operation of other blows all tending to release the strike condition.

A more detailed description of the invention emphasizing the above objects, and others, together with a complete disclosure of the structure and function, follows as a description of the accompanying drawing, in which:

Figure 1 is an axial section through the jar incorporated in a drill string as it passes downwardly in well tubing;

Figure 2 is an axial section showing the jar in operation; and

Figure 3 is a sectional view of the magnetic means employed, taken on line 3—3 of Figure 1.

The device of this application is illustrated in one form as it would appear as part of a tool string being lowered into tubing 10 which is suspended in casing 12 in a well bore hole. A wire line 14, normally of small diameter to pass through a packing gland for conservation purposes, is the means of connecting tools or other exploratory elements diagrammatically shown as number 16 with the surface.

Between the lower end of the wire line 14 and the tool 16, the jar mechanism of this application, generally denoted by the inclusive number 18, is positioned. A tubular body portion 20 is fashioned at the lower end 22 to support a tool or other device 16. As shown this can be in the form of a solid section reduced in diameter to meet the connected tool, being drilled and tapped as at 24 for such tool engagement. The lower portion of the tube 20 is thus shown to be of solid structure in this embodiment. However, it will be evident that it can be an open cage-like structure for easy passage of liquids and gases through the tubular body portion 20.

This section of the body portion, in addition to mount-

2

ing the suspended tool 16, is designed to hold a permanent magnet 26 forming a restraining means for use in the jarring operation. Set screws 28 hold this magnet in operating position in the bottom of the body portion 20.

Magnet 26 is of the well-known concentric pole construction which lends itself particularly well to the tool jar of this application. Other forms of permanent magnets can be used if desired without changing either the general construction or operating principles disclosed here. This form of magnet used in cooperation with a like magnet with reversed poles, conserves the magnetic field for maximum operating efficiency as will be fully understood on reading the following additional descriptive material.

Slidably movable in the tubular body portion 20, hammer means 30 extends into engagement with the wire line 14. The second permanent magnet 32 of reversed pole pieces, as indicated in Figure 2, forming a complementary element in the restraining means, is fastened to the hammer means 30. One form of connection between the magnet 32 and the hammer 30 is shown here as a threaded stud 34 adapted to engage a like threaded hole in the magnet. The portion 36 of the hammer 30 is enlarged to assist in keeping the hammer aligned in the tubular body 20 as it slidably moves therein, and also presents the hammer head 38 which strikes against the anvil 40. A reduced portion or handle 37 of the hammer connects with the head 38 and extends upwardly through the annularly formed anvil 40 into operating contact with the wire line 14. By threadedly engaging the annular anvil 40 as at 42 with tubular body 20, the impact of the hammer head 38 is transmitted through the jar tool to the suspended tool 16, as will be disclosed in the description of operation. The anvil is apertured as at 44—44 to receive a spanner wrench for keeping the anvil 40 securely in place.

Above the anvil, the extending portion of the hammer means 30 is shown enlarged at the wire line anchorage portion 46 and headed at 48 where wire line 14 is received. One form of securing the wire line 14 is shown inside anchorage portion 46 to include a ball end 45 fastened to the end of wire line 14 which bears against washer 43 and compression spring 41. By such an arrangement the jar 18 is resiliently supported within the tubing 10. This structure diagrammatically illustrates an engaging means for the wire line and hammer which can be easily changed with any desired mechanical adaptation. Additionally the enlarged portion 46 adds weight to the hammer 30 increasing the inertia of this slidable element assisting in the jarring action.

Figure 2, compared with Figure 1, forms the basis for describing the operation of the device. To indicate a condition of improper operation such as sticking of the tool 16 preventing wire line movement to continue the operation, the jar and tool are shown askew in the tubing 19. In order to free the tool, wire line 14 is tightened until the magnetic field between the two magnets 26 and 32 is initially overcome, separating them.

The well known laws of the strength of attracted magnetic fields enables the calculation of the force necessary to initially separate these magnets. Once separated, the magnetic effect decreases directly in proportion to the square of the distance between the magnets. As the magnets separate the restraint of each upon the other rapidly diminishes and the hammer means 30 moves with increasing rapidity into engagement with the anvil 40. The resulting blow is sharp and unrestrained. The force of the blow is in direct proportion to the amount of force required to initially separate the two magnets 26 and 32. Figure 2 shows the hammer head 38 and anvil 40 in striking position, the upper end of hammer means 30 and wire line 14 omitted for lack of space.

Having delivered the blow, wire line 14 is slackened and the hammer means 30 with attached magnet 32 is permitted to slide downwardly in the tubular body 20, the stuck condition assumed to be unrelieved at this moment. As magnet 32 slides downwardly to join its magnetic influence with the field of magnet 26, the magnetic attraction between the magnets becomes stronger and stronger. This attraction increases in reverse of the separating influence discussed above, culminating in electrical engagement with full force on contact. Repeated blows and returns to the restrained position, making these blows effective, will release the bound tool.

From the above description of the device and its operation, it will be evident that the jarring tool of this invention has many advantages over those presently known. The magnets, creating the restraint which makes the final jarring blow so effective, require no positive return to the starting position for latching, collapsing, or other action. Contact will be made between the magnets and the restraining force, reestablished on the lightest touching, and assisted, magnetically, to assume the beginning of the operation.

Further, the strength of the restraining force can be varied within desired ranges by selection of different strength magnets. Once the wire line 14 is selected as proper for operating this jarring tool, the line will not be parted because of a latch not working or some other obstruction to a mechanical releasing mechanism.

Modifications of the above disclosed preferred embodiment of this device will be immediately evident to those versed in the art. In addition to changing the shape of the magnets previously mentioned, changes, such as omitting one magnet as a means for reducing the restraining force, will be evident. Alterations of this type have been considered by the applicant and are considered as being within the scope of this disclosure.

In general it will be evident, as indicated above, that the present device is capable of many alterations in shape, number and type of elements, as well as miscellaneous

elements being added or omitted to facilitate operation, without adding to or changing the spirit of the invention disclosed here. It is the intention of the inventor, therefore, to be limited only by the scope of the appended claims.

What is claimed is:

1. A wire line tool jar comprising an elongated tubular body, coupling means on the lower end of said tubular body attachable to a tool, an elongate hammer means 10 slidably operable in said tubular body, wire line fastening means on the upper end of said elongate hammer means and a head on the lower end, an anvil closing the upper end of the tubular body about the hammer means in position to be struck by the hammer head, opposed magnets 15 separately fixed in the tubular body and on the hammer head respectively magnetically restraining the relative sliding movement of the hammer and the tubular body.
2. A wire line tool jar comprising elongate hammer means having a head on the lower end and adapted to fasten to a wire line on the other end, a tubular body 20 positioned in relative sliding cooperation with said hammer, tool mounting means on the bottom of the tubular body, an annular anvil closing the top of the tubular body about the elongated hammer means between the upper 25 and lower ends, and magnetic means in the tubular body cooperatively restraining the relative sliding motion of the hammer and tubular body.
3. The jar of claim 2 further characterized by said magnetic means cooperatively restraining the relative sliding motion of the hammer and tubular body including opposed permanent magnets of different polarity separately fixed to said hammer and tubular body respectively.
